WALLACE L. CLAYPOOL, OF DAVENPORT, IOWA, ASSIGNOR TO WESTCO-CHIPPEWA PUMP COMPANY, OF DAVENPORT, IOWA, A CORPORATION OF DELAWARE

ROTARY PUMP

Application filed March 18, 1930. Serial No. 436,732.

This invention relates to rotary pumps and more particularly to pumps comprising a rotor having a liquid impelling means such as a plurality of marginal buckets operating in a liquid passage.

One of the objects of the present invention is to provide simple and effective means for priming a pump of the rotary type having a pressure building chamber and a rotor operable therein.

Another object is to provide a rotary pump with means which will prevent interruptions in the operation of the pump such as the losing of its prime.

Another object is to provide a rotary pump in combination with a pressure supply system in which the supply tank has a connection independently of the discharge outlet with the liquid passage of the pump to maintain the pump in primed condition, while the pump is in operation.

A further object is to provide a rotary pump of the type having a rotor which operates in a substantially closed liquid passage with priming means so arranged that priming liquid may be admitted at the bases of the rotor buckets, whereby such liquid may be utilized to maintain the pump in primed condition while in operation.

With the foregoing and other objects in view, which will be apparent from the detailed description to follow, this invention consists in certain novel features of construction and combinations of parts which will be readily understood by those skilled in the art to which the invention appertains.

In the accompanying drawings which illustrate suitable embodiments of the present invention,

Figure 1 is an elevation of a liquid pressure supply system showing the supply tank and the rotary pump for supplying liquid to the tank.

Fig. 2 is a fragmentary elevation of the lower portion of the supply tank taken substantially 90 degrees to Fig. 1 showing the end elevation of the rotary pump and showing the priming connection between the tank and pump.

Fig. 3 is an enlarged fragmentary section

of the rotary pump taken substantially on the line 3—3 of Fig. 1, showing one of the pump casing sections and the rotor mounted therein, a portion of the rotor being broken away to show the connection for the priming means. 55

Fig. 4 is an enlarged section of the pump taken substantially on the line 4—4 of Fig. 2.

Fig. 5 is an enlarged section taken substantially on the line 5—5 of Fig. 3, showing the connections of the priming conduits with the 60 casing sections.

Fig. 6 is an elevation of an optional fluid pressure supply system wherein the means for priming the rotary pump admits priming fluid to the pump casing radially inwardly of 65 the fluid passage therein.

Fig. 7 is an enlarged view of one of the casing sections of Fig. 6 showing the rotor mounted therein.

Fig. 8 is a section taken substantially on 70 the line 8—8 of Fig. 7 to show the connections of the priming conduits.

Referring to the drawings, in which like numerals refer to like parts throughout the several views, the casing body 1, supporting 75 base 2, and a shaft supporting bracket 3 are cast integrally. The casing 1 is saucer-shaped and has a peripheral rim 4 having a flat peripheral side face 5, and an internal peripheral channel 6 which forms the fluid 80 passage, the outer wall of which may be formed by a radially extending rib 7, the rib 7 having a cylindrical inner edge. The web portion of the casing body has upon the inner face thereof a relatively low annular rib 85 8 concentric with the rim 4. The casing body 1 has an axial integral tubular boss 9 on the outer side thereof, and the bracket 3 has a bearing aperture in axial alignment with the boss 9. 90

The casing cover 10 is formed with an axial integral tubular boss 11 in axial alignment with the boss 9 of the casing 1 and with an integral shaft supporting bracket 12 having a bearing aperture at its outer end in axial 95 alignment with the boss 11. The casing cover 10 also has its inner face circumferentially rabbeted to provide a cylindrical shoulder 13 to fit within the cylindrical inner edge of the rib 7 and a flat peripheral portion 14 to 100

fit against the flat face 5 of the casing body 1. The cover portion also has upon the inner face thereof a relatively low annular rib 15 concentric with the rabbeted shoulder 13 and of the same diameter as the shoulder 8 formed on the casing body 1.

The contiguous faces 5 and 14 of the casing body and cover, respectively, are preferably provided with registering grooves which 10 form an annular packing chamber for receiving an annular packing member 16, so that an effective water-tight seal is provided between the casing body and cover. The casing body and cover are securely held together 15 in assembled relation by means of suitable bolts or cap screws 17.

A shaft 19 is journaled axially in the casing body and cover and in bearing members mounted in the bearing apertures of the 20 brackets 3 and 12. Suitable packing gland nuts 22 surrounding the shaft 19 and extending into the tubular bosses 9 and 11 are provided to prevent the escape of the liquid from the interior of the pump body. The portions 25 21 of the bosses 9 and 11 forming the abutments for the packing has a slight working clearance only with the shaft so as to prevent the packing from being forced into the pump. The rotor for the pump is mounted within the 30 casing body 1 and comprises a circular disk having a hub 18, web 23 and an outer peripheral portion 24 upon the outer edges of which the impeller ribs 25 are formed. The annular portion 24 of the rotor has a close working 35 fit between the annular ribs 8 and 15 of the casing body 1, and casing cover 10, whereby the annular liquid passage 6 is substantially cut off from the central portion of the casing.

40 As shown in Fig. 3, the impeller ribs 25 extend laterally from the portion 24 and lie within the liquid passage 6. The impeller ribs 25 are formed at both sides of the peripheral edge of the rotor to form suitable buckets, the side edges of which are spaced from the side walls of the passage 6 and the peripheral edges of which are spaced from the circumferential wall of the passage 6.

45 The casing body 1 is provided with outlet and inlet portions 26 and 27, respectively, which communicate substantially tangentially with the liquid passage 6. An abutment 50 28 is positioned in the liquid passage 6 between the outlet 26 and inlet 27 and has a close working fit with the sides of the rotor ribs 25 and is provided with a shoulder portion 29 which also has a close working fit with 55 the peripheral edges of the rotor ribs 25 so that the liquid being pumped will be deflected from the liquid passage 6 into the outlet 26. The cover portion 10 is provided with an outwardly extending radial continuation of the 60 annular rib 15 to correspond with the abut-

ment 28, which also has a close working fit with the adjacent side of the rotor ribs 25.

The rotary pump just described is mounted upon a suitable base 30 and is driven by means of any prime mover, such as the electric motor 31, the shaft 32 of which is in axial alignment with the shaft 19 of the pump and connected thereto by means of a suitable coupling 33.

70 The outlet 26 of the casing body 1 is connected through a conduit 34 to the bottom of the pressure supply tank 35. The inlet 27 of the pump is connected to a conduit 36 which leads to the well from which the liquid is to be pumped and the conduit 36 is provided with a suitable check valve 37 which prevents the flow of liquid from the pump back through the conduit 36. The supply tank 35 is of the pressure type and is provided with a suitable pressure responsive switch 38 which is connected to the motor 31 so that when the pressure within the tank reaches a predetermined amount, the pressure responsive switch 38 will close the electric circuit 80 and start the motor and pump in operation.

85 The pump is primed while in operation by a means independent of the liquid discharge outlet, which will now be described. This means is so arranged that fluid in the supply tank is conducted back to the liquid passage 6 of the pump casing at the discharge side thereof immediately adjacent the stop means. A portion of the returned liquid enters the rotor buckets just as they are about to pass the stop means and is carried past the stop means to the inlet side of the liquid passage, so that it can be utilized to prime the pump in case the operation thereof is interrupted. The most efficient operation is provided by admitting the liquid substantially normal to the plane of the motor and at the bases of the buckets. It is to be understood, however, that the priming fluid may be admitted at an angle to the rotor and at any point adjacent the stop means.

90 A threaded opening 39 is formed in each side wall of the pump casing into which a suitable conduit 40 is threaded. The conduits extend upwardly to the bottom of the supply tank 35 and are secured thereto to receive liquid from the tank. As shown in Figs. 3 and 5, the openings 39 communicate with the fluid passage 6 at the inner side thereof immediately adjacent the connection of the stop means shoulders 29 with the ribs 8 and 15 of the body and cover portions, respectively, of the casing. The openings 39 are preferably partially formed in these connections so that the priming liquid will enter the buckets just as the impeller ribs are about to engage the shoulders 29 of the stop means 28.

100 While the pump is in operation the priming liquid is conducted from the supply tank 35 through the conduits 40 to the bottoms of the rotor buckets 25 and because of the fact 105

that the priming liquid enters these buckets immediately adjacent the stop means 28 and shoulders 29 thereof, a portion of the liquid is retained within the buckets while traveling 5 past the shoulder portion 29 to the inlet side of the liquid passage 6 and may be effectively utilized to prime the pump.

In the cases where pump loses its prime, either while idle or in operation, the rotor buckets when the rotor is operating trap 10 pockets of air between slugs of liquid and also gather air with the liquid in the form of a mist and emulsion. This mixture of air and liquid is discharged at the outlet by 15 displacement of the liquid entering through the conduits 40 from the tank 35, thus refilling the rotor buckets as they move past the stop means. The rotor buckets thus 20 maintain the liquid passage 6 partially full of liquid to prevent the pump from pumping air only.

In the particular construction shown in Figs. 1 and 2, the bottom of the pressure supply tank is positioned above the level of the 25 pump outlet and the liquid is discharged from the pump into the bottom of the tank.

In Figs. 6, 7 and 8, a slightly modified construction is shown to comprise a tank into which the liquid is discharged through a side 30 thereof. The casing body and cover portion of the pump are substantially the same construction as the pump described in connection with Figs. 3 to 5, and need not be described in detail. A suitable liquid receiving chamber 50 is provided between the pump outlet 51 and the pressure supply tank 22, and with a standpipe 70, so that a substantial quantity of liquid is retained within the chamber 50. This liquid receiving chamber 35 is provided with conduits 53 leading substantially from the bottom thereof to the pump casing body 54 and the cover 55. These conduits enter into the casing body 54 and the cover 55 through openings 56 and 57, respectively, formed radially of the passage sealing ribs 58 and 59 provided on the casing body and cover. The sealing ribs are provided with passages 60 at the outlet side of the pump immediately adjacent the liquid 40 deflecting stop means 61 thereof, which connect the liquid passage 62 with the chamber 63 provided at the opposite side of the ribs 58 and 59. The rim of the rotor 64 is connected to the hub 65 thereof by means of 45 a narrow web having curved spoke portions 66 extending transversely thereof, each of which is provided with a transverse flange or paddle portion 67.

When the pump is in operation, liquid 50 within the fluid receiving chamber 50 is conducted therefrom through the conduit 53 to the chamber 63 radially inwardly of the sealing ribs 58 and 59. The liquid discharged 55 into this chamber 63 is set in centrifugal motion by means of the paddles 67 formed on

the spokes 66 of the rotor, and is discharged through the passages 60 at the sides of the rotor buckets. Since these passages are formed in the ribs 58 and 59 adjacent the deflecting portion 61 of the pump, the liquid will be 60 lead into the bottoms of the rotor buckets and will be carried past the stop means 61 to the inlet side of the pump, whereby the liquid will provide effective means for priming the 65 pump.

It is to be understood that the conduits 51 may, if desired, be led to discharge directly into the liquid passage, as in the previously described construction shown in Figs. 1 to 5.

In each of the constructions described, a separate means independent of the discharge outlet is provided for admitting liquid to the buckets, preferably at the bottom thereof, and adjacent the stop means, so that the liquid is directed into the rotor buckets and 80 carried thereby past the stop means to the inlet side of the liquid passage. This liquid is utilized in priming the pump when the 85 operation thereof is interrupted.

The present invention provides a very satisfactory and efficient self-priming means 90 for rotary pumps of the type described.

Furthermore, it is to be understood that the particular forms of apparatus shown and described, and the particular procedure 95 set forth, are presented for purposes of explanation and illustration and that various modifications of said apparatus and procedure can be made without departing from my invention as defined in the appended 100 claims.

What I claim is:

1. In a rotary pump, a casing, a pressure developing passage in said casing having an inlet and an outlet, stop means between said 105 inlet and outlet for directing fluid into said outlet, a rotor having marginal rotor buckets, said rotor and casing being sealed to prevent substantial leakage of liquid radially inwardly of said passage, and a second inlet 110 independent of the discharge outlet communicating with said passage, said second inlet being so positioned as to permit the entrance of liquid to said buckets, whereby said liquid may be carried past said stop means to the 115 inlet side of said passage.

2. In a rotary pump, a casing, a pressure developing passage in said casing having an inlet and an outlet, stop means between said 120 inlet and outlet for directing fluid into said outlet, a rotor having marginal rotor buckets, said rotor and casing being sealed to prevent substantial leakage of liquid radially inwardly of said passage, and a second inlet independent of said outlet in said casing and adjacent said outlet, said inlet being so positioned as to admit priming fluid to the bases 125 of said buckets, whereby said liquid may be carried past said stop means to the inlet side of said passage.

3. In a rotary pump, a casing, a pressure developing passage in said casing having an inlet and an outlet, stop means between said inlet and outlet for directing fluid into said outlet, a rotor having marginal rotor buckets, said rotor and casing being sealed to prevent substantial leakage of liquid radially inwardly of said passage, and a second inlet independent of said outlet in said casing communicating with said passage adjacent said outlet and being partially formed in said stop means whereby liquid is admitted to said buckets and carried past said stop means to the inlet side of said passage.
4. In a rotary pump, a casing, a pressure developing passage in said casing having an inlet and an outlet, stop means between said inlet and outlet for directing fluid into said outlet, a rotor having marginal rotor buckets, said rotor and casing being sealed to prevent substantial leakage of liquid radially inwardly of said passage, and a second inlet in said casing independent of said outlet communicating with said passage adjacent said outlet and at the junction of said stop means with the inner wall of said passage to admit liquid to said buckets, whereby said liquid may be carried past said stop means to the inlet side of said passage.
5. In a rotary pump, a casing, a pressure developing passage in said casing having an inlet and an outlet, stop means between said inlet and outlet for directing fluid into said outlet, a rotor having marginal rotor buckets, said rotor and casing being sealed to prevent substantial leakage of liquid radially inwardly of said passage, and a second inlet in said casing independent of said outlet communicating with said passage adjacent said outlet and immediately adjacent said stop means substantially normal to the plane of said rotor for admitting liquid to said buckets, whereby said liquid may be carried past said stop means to the inlet side of said passage.
6. In a rotary pump, a casing, a pressure developing passage in said casing having inlet and outlet passageways, a stop means within said passage between said inlet and outlet passageways for directing liquid into said outlet, a rotor sealed with said casing radially inwardly of said passage to obviate leakage of liquid from said passage, said rotor having a series of radial marginal buckets at each side thereof, and secondary inlets at opposite sides of said casing communicating with said passage adjacent said outlet passageway, each of said secondary inlets being disposed to admit liquid to a series of buckets adjacent said stop means, whereby said liquid may be carried past said stop means to the inlet side of said passage.
7. In a rotary pump, a casing, a pressure developing passage in said casing having inlet and outlet passageways, a stop means within said passage between said inlet and outlet passageways for directing liquid into said outlet, a rotor sealed with said casing radially inwardly of said passage to obviate leakage of liquid from said passage, said rotor having a series of radial marginal buckets at each side thereof, and secondary inlets at opposite sides of said casing communicating with said passage adjacent said outlet passageway, each of said secondary inlets being disposed to admit liquid to a series of buckets adjacent said stop means, whereby said liquid may be admitted thereto and carried thereby past said stop means to the inlet side of said passage.
8. In a rotary pump, a casing, a pressure developing passage in said casing having inlet and outlet passageways, a stop means within said passage between said inlet and outlet passageways for directing liquid into said outlet, a rotor sealed with said casing radially inwardly of said passage to obviate leakage of liquid from said passage, said rotor having a series of radial marginal buckets at each side thereof substantially normal to the plane of said rotor, and secondary inlets at opposite sides of said casing communicating with said passage adjacent said outlet passageway, each of said secondary inlets being disposed to admit liquid to the bottoms of said buckets immediately adjacent said stop means, whereby said liquid may be carried past said stop means by said buckets to the inlet side of said passage.
9. In a rotary pump, a casing, a pressure developing passage therein having an inlet and an outlet, a rotor for said passage sealed with said casing radially inwardly of said passage to obviate leakage of liquid from said passage, said rotor having a series of radial marginal buckets lying within said passage, the walls of said passage being radially and laterally spaced from said buckets, stop means between said inlet and outlet for directing liquid into said outlet, said stop means engaging the periphery and opposite sides of said rotor with a running fit, and secondary inlets at opposite sides of said casing communicating with said passage adjacent said outlet passageway, each of said secondary inlets being adjacent said stop means and adjacent the bottoms of the rotor buckets, whereby liquid may be admitted thereto and carried thereby past said stop means to the inlet side of said passage.
10. In a fluid pumping and storage supply system, the combination with a fluid storage tank, of a rotary pump comprising a casing having a pressure developing passage, an outlet for said casing communicating with said storage tank, an inlet communicating with a source of liquid supply, stop means between said inlet and outlet for directing liquid into said outlet and a rotor having marginal radial blades surrounded by said pas-

sage, and means for conducting liquid from said tank to said passage immediately adjacent said stop means at the discharge side thereof, whereby the liquid returned from said tank may be admitted to said buckets and carried thereby past said stop means to the inlet side of said passage to prime said pump.

11. In a rotary pump, a casing having a pressure developing passage therein, an inlet and outlet for said passage, stop means within said casing between said inlet and outlet for directing liquid into said outlet, a rotor having radial marginal buckets lying within said passage, said rotor being sealed at its sides with said casing radially inwardly of said passage to obviate the leakage of liquid from said passage, a chamber in said casing radially inwardly of said passage, a passageway leading from said chamber to said passage at the discharge side of said passage immediately adjacent said stop means, means for admitting liquid to said chamber, and means on said rotor for discharging the liquid in said chamber into said passageway and into said buckets, whereby the liquid may be carried by said buckets past said stop means to the inlet side of said passage.

12. In a rotary pump, a casing, a pressure developing passage in said casing having an inlet and an outlet, stop means between said inlet and outlet for directing fluid into said outlet, a rotor having marginal rotor buckets, said rotor and casing being sealed to prevent substantial leakage of liquid radially inwardly of said passage, and a second inlet independent of the said outlet and inlet for said passage and communicating with the pressure discharge side of said passage for returning discharged liquid to said passage to maintain said pump in primed condition.

In testimony whereof I affix my signature.
WALLACE L. CLAYPOOL.
